UNITED STATES PATENT OFFICE

110,858

DESIGN FOR A TOY ROTARY UNIT

Clifford Egerton, Forest Hills, Long Island, N. Y.

Application July 2, 1937, Serial No. 70,215

Term of patent 14 years

To all whom it may concern:

Be it known that I, Clifford Egerton, a citizen of the United States of America, residing at Forest Hills, L. I., county of Queens, and State of New York, have invented a new, original, and ornamental Design for a Toy Rotary Unit, of which the following is a specification, reference being had to the accompanying drawing, forming part thereof.

Figure 1 is a plan view of a toy rotary unit showing my new design.

Figure 2 is a side elevation of the toy rotary unit of Figure 1.

I claim:

The ornamental design for a toy rotary unit, as shown.

CLIFFORD EGERTON.
